CHARGING DEVICES FOR A FIREARM

Burns Darsie, Watertown, Conn., assignor to the United States of America as represented by the Secretary of the Army

Filed June 18, 1953, Ser. No. 334,764

16 Claims. (Cl. 89--1)

The present invention relates to automatic firearms and more particularly to firearm charging devices.

The present invention is primarily concerned with gun chargers for machine guns or the like having a reciprocating member, such as a bolt, that reciprocates between a battery and recoil position.

In charging firearms such as machine guns of large caliber, it is first necessary to retract the bolt from the battery position to insert the first cartridge in the chamber to start firing. The normal reciprocation of a bolt in a firearm is actuated by the firing of a cartridge. However, to load the firearm with each new string of cartridges, the bolt must be retracted and it is preferred to use an automatic charging device for this operation, thereby eliminating the necessity of the gunner using manual means.

In certain installations where several firearms are grouped together in confined quarters of a vehicle or plane, it is necessary to operate such firearms at a distant point due to such confined quarters.

It is therefore an object of this invention to provide a charging device which may be efficiently operated from a distant point with remote control for charging a firearm.

Another object of this invention is to provide a simple, rugged and inexpensive charging device for an automatic firearm.

Another object of this invention is to provide a charger with a minimum number of parts of light weight and likely to require very little if any attention as far as repairs are concerned, as no springs are used to actuate the device disclosed herein.

A further object of this invention is to provide a charging device constructed in such a manner that it does not change the outside configuration of the firearm structurally.

A particular object of this invention is to provide double action screw means for moving the bolt from a battery to a recoil position and vice versa.

Another particular object of this invention is to provide a pneumatic device that is exceedingly compact and is of such shape and size that it can be readily assembled inside the receiver in such a manner that it does not interfere with and/or function with the operating parts, while such parts are reciprocating in the receiver during the normal functioning of the gun.

Still another object of this invention is the provision of a device that will hold the bolt in a retracted or recoil position and also will hold such bolt in the battery position.

An important object of this invention permits the assembling of two synchronized pneumatic or hydraulic charging devices on the inside of the receiver, one on each side thereof to cooperate with downwardly depending lugs on each side of the bolt, thereby obtaining a direct uniform pull and/or push on the bolt. In prior art when a charging device was used on one side only, an uneven push or pull on the bolt resulted, thereby causing a wedg-

ing action of the bolt that naturally decreased the cyclic rate of the firearm.

Another very important object of this invention resides in the cylinder and piston arrangement which provides a greater force on the charger nut to retract the bolt to the recoil position than is provided to move the bolt into the battery position.

Still another very important object of this invention resides in the double acting screw and nut mechanism operated by fluid pressure in such a manner that the travel of the charger nut is nearly twice the travel of the piston which operates such charger.

The specific nature of the invention as well as other objects and advantages thereof will clearly appear from a description of a preferred embodiment as shown in the accompanying drawings in which:

Fig. 1 shows a partial sectionalized longitudinal view with the bolt in the recoil position;

Fig. 2 is a similar view of Fig. 1 with the bolt in the battery position;

Fig. 3 is a rear end view showing the relation of the chargers with the bolt;

Fig. 4 is a schematic view showing the means for supplying the air in the recoil and counter-recoil action of the charger cylinders;

Fig. 5 is a bottom perspective view of the bolt showing the bolt lugs and latches therein;

Fig. 6 is a front end view of the bridge; and

Figure 7 is a section to an enlarged scale taken along lines 7-7 of Figure 6 and showing the chargers in relation to the receiver, an intermediate part being broken away.

Referring to the drawings, reference numbers 12, 14 and 16 designate the receiver, charger assembly left hand and charger assembly right hand, respectively. Reference numeral 18 designates a bolt assembly that is mounted in receiver 12 for reciprocating movements between a battery and recoil position and that does not require the use of driving springs to return the bolt to the battery position, depending instead upon the impact force on the buffer mechanism, whereby the rebound returns said assembly to the battery position.

Bolt assembly 18, on the extreme rear end, is provided with a pair of downwardly depending charger lugs 20 from the bottom thereof, spaced an equal distance apart from the longitudinal central line of such assembly. Bolt assembly 18, forwardly of lugs 20, is provided with a pair of slots 22 positioned longitudinally parallel with charger lugs 20. Each slot 22 is arranged to pivotally receive a spring-biased latch assembly 24 for a purpose to be described later. Bolt assembly 18 is provided on the left side thereof with an electrical contact 26 arranged to propel a conventional firing pin forwardly to discharge a cartridge when energized by an electrical source (not shown).

Receiver 12 is of U-shaped structure having a bottom plate 28 and upwardly extending plate portions 30 and 32 on the left and right hand side thereof, respectively. Receiver 12 is also provided with a cover 34 having downwardly depending side plates on the left and right hand side thereof, designated by the numerals 36 and 38, respectively, that are secured to plates 30 and 32, respectively. Receiver 12 is provided with a lower buffer bracket 40 extending upwardly from the bottom plate 28 in the center thereof and longitudinally positioned therein. An approximate cylindrical bore 42 is provided on each side of lower buffer bracket 40 longitudinally disposed, and constructed to receive one of the charger assemblies 14 or 16 in their respective positions.

Vertically above each of bores 42, there is provided a longitudinally disposed shelf 44 having vertical and horizontal planar surfaces at right angles to each other, ar-

ranged to slidably receive bolt assembly 18. Receiver 12 is also provided with an upper buffer bracket 46 longitudinally disposed vertically above lower buffer bracket 40 and having a bottom surface constructed to complete in cooperation with shelves 44 an oblong opening 52, substantially large enough to permit the reciprocation of the bolt assembly 18 therein. Receiver 12 is also provided, on the left side of opening 52, with a longitudinally disposed recess 54 to permit the passage of contact 26 therethrough, while bolt assembly 18 is reciprocating from a battery to a recoil position and vice versa.

A pneumatic or hydraulic charger valve assembly 48 is secured to plate 32 on the right hand side of receiver 12 and is operated by a conventional solenoid 50 for controlling the air or oil impulses for the functioning of charger assemblies 14 and 16 that will be described in more detail later. The preferred embodiment as disclosed herein will hereafter refer to the pneumatic charger valve assembly only with the use of air as a medium for functioning the chargers. A charger bridge 56 is secured to the lower front end of receiver 12 and is provided with a pair of spaced-apart cylindrical recesses 58 in alignment with bores 42 of receiver 12 and being of approximately equal diameter as bores 42.

Charger assembly 16, located on the right side of receiver 12, comprises basically a tubular charger cylinder 60, an outer piston 64 and an inner piston 66. Tubular charger cylinder 60, right hand, is of such diametrical proportions as to be received in bore 42 of receiver 12 and the front end of said cylinder is fixedly secured in recess 58 of charger bridge 56. Cylinder 60 is provided with an elongated slot 62, extending from the rear end to approximately half the entire length in the upper part thereof, the center line of which is positioned on the left side of the longitudinal center line of such cylinder.

Inner piston 66, used in both charger assemblies 14 and 16, is provided with a reduced front end 74, fixedly secured in a bore 68 of bridge 56, aligned with and forwardly of each recess 58, and an enlarged rear end or head 70 arranged to slidably engage in outer piston 64. Outer piston 64 is provided with a longitudinal bore 72 for cooperation with head 70 of piston 66. Piston 64 is provided with a reduced bore 78 on the front end thereof, communicating with bore 72 and arranged to slidably receive an intermediate portion 76 between head 70 and end 74 of piston 66. An interior annular groove 166 is positioned in bore 78 and is arranged to receive a ring packing 168. Piston 64 also has an exterior annular groove 170 positioned radially from groove 166 and arranged to receive a ring packing 172. Head 70 of piston 66 is provided with an annular groove 80, around the outer periphery thereof, to receive a ring packing 82. An air sealing plug 84 is threadably secured in the rear end of bore 72 of piston 64. Piston 64 is provided with an offset upstanding bracket 86, projecting upwardly through cylinder slot 62 and having a bore 88 in the upper part thereof, arranged to receive a ball bearing 90.

Approximately vertically above the cylindrical recess 58, on the right hand side of bridge 56, and horizontally aligned with bore 88 of bracket 86, a hole 92 is provided to receive a reduced end portion 94 of an inner screw 96. End portion 94 is fixedly secured in hole 92 through the medium of a pin 98. Inner screw 96 is provided with left hand threads 100 on the exterior thereof to cooperate with interior threads 102 provided on an outer screw 104, that is rotatably mounted thereon. Outer screw 104 is provided with a plug 106 in the rear end thereof that is fixedly secured to ball bearing 90 for rotation therewith. A charger nut 108, having right hand threads 182, is threadably mounted on outer screw 104 which is also provided with right hand threads 184 whereby rotation of screw 104 traverses nut 108 therealong. Charger nut 108 is provided with an upwardly extending lug 160 on the left side thereof for cooperation with lug 20 and latch

assembly 24 on the right side of bolt assembly 18 for a purpose to be described later.

Charger assembly 14, located on the left side of receiver 12, is similar in structure and elements to charger assembly 16, but with the following exception. Tubular charger cylinder 110, left hand, is identical with charger 60, except that the slot 112 in the upper part thereof, is positioned on the right side of the longitudinal center line of such cylinder. Outer piston 114 is provided with an offset upstanding bracket 116, projecting upwardly through cylinder slot 112, of tubular charger cylinder 110 and is provided with a bore 88 in the upper part thereof. Charger bridge 56 is provided with a hole 118, located approximately above cylindrical recess 58 on the left side of such bridge and being in alignment with bore 88 located in bracket 116, such hole being arranged to receive end 94 of inner screw 96. A charger nut 162 is threadably mounted on outer screw 104 of charger assembly 14 for traversing therealong and is provided with an upstanding lug 164 on the right side thereof for cooperation with lug 20 and latch assembly 24 on the left side of bolt assembly 18 for a purpose to be described later.

Charger valve assembly 48 is designed with a valve mechanism (not shown as it does not form a part of this invention) that is actuated by a solenoid 50, whereby a high pressure air impulse is either permitted to enter the recoil side of the system through orifice 120 or the counter-recoil side through orifice 122 as selected, both being located in the right side plate portion 32. Orifice 120 connects with a downwardly depending passage 124 that is joined at right angles by a recoil duct 126 leading forwardly therefrom and terminates in charger bridge 56. Orifice 122 connects with a downwardly depending passage 128 that is joined at right angles with a counter-recoil duct 130 leading forwardly therefrom parallel with and below duct 126 and terminates in charger bridge 56.

Counter-recoil duct 130 connects with a tunnel 132 in charger bridge 56 that terminates in each of bores 68 and registers with a radially disposed hole 134 located in end 74 of piston 66. Hole 134 communicates with a longitudinally disposed channel 136 that extends rearwardly therefrom and terminates in a radially disposed orifice 138 positioned directly in front of head 70. Piston 66 is also provided with a longitudinally disposed exhaust conduit 140, juxtaposed to channel 136, leading from the rear end and terminating in a radially disposed hole 142 positioned at the junction of intermediate portion 76 and end 74.

Recoil duct 126 connects with a tunnel 144 in charger bridge 56 that terminates in a cavity 146 rearwardly of each bore 68 and leading into recess 58. The forward ends of cylinders 60 and 110 are provided with a disc 148 having a cylindrical bore 150 therethrough to receive end 74 of piston 66. Disc 148 is provided with a series of angularly disposed holes 152, in relation to the horizontal center line, for the admittance of high pressure air impulses therethrough. Forwardly of disc 148, cylinders 60 and 110 are provided with a series of radially disposed holes 154 leading outwardly from the interior thereof, arranged to allow the exhausting of air pressure therefrom on the counter-recoil cycle. Forwardly of disc 148 and within the interior of cylinder 60 there is assembled on end 74, a check valve assembly 156 provided to allow air pressure to pass through angular holes 152 that is in turn impinged against a forward end 158 of outer pistons 64 or 114 for actuating such pistons to the recoil position.

Operation

To withdraw bolt assembly 18 from the battery position in charging the gun, solenoid 50 actuates the valve mechanism permitting an air impulse to enter orifice 120 on the recoil side of the system. This air impulse descends down through passage 124 through duct 126 and

into tunnel 144 in charger bridge 56. The air impulse opens the valve assembly 156 by the action of the air against such assembly and then passes through holes 152 and against ends 158 of outer pistons 64 and 114 thereby actuating such pistons to the recoil position. When valve assembly 156 is being opened, it moves rearwardly thereby blocking off holes 154 as shown in Fig. 1 thus preventing the escapement of air to atmosphere. During the recoil movement of said pistons, a portion of the air enters hole 142 passing through conduit 140 and impinges upon the forward surface of plug 84, thereby applying an additional pressure to move said pistons rearwardly providing a greater force than the force applied during counter-recoil. The trapped air between head 70 of inner piston 66 and the inner front wall in longitudinal bore 72 of piston 64 is permitted to escape through orifice 138 through channel 136 and out hole 134 into the counterrecoil side of the system to exhaust into the atmosphere.

To return the bolt to the battery position, the solenoid actuates the valve mechanism in such a manner as to exhaust air from passage 120 and to permit air to enter the counter-recoil side of the system passing through orifice 122, passage 128, duct 130 and into tunnel 132 in charger bridge 56. The air then passes through hole 134 along channel 136 and out orifice 138 and such air then impinges upon a wall 174 in the forward part of longitudinal bore 72, thereby forcing piston 64 forwardly to the battery position with a lesser force than applied during recoil. The trapped air between a rear end 176 of piston 66 and a forward end 178 of plug 84 is exhausted through conduit 140 and out hole 142. This trapped air then passes out through holes 152 actuating valve 156 forwardly thereby closing same and permitting the trapped air to escape through holes 154. The trapped air between the forward end 158 of piston 64 and the rear face 180 of disc 148, also escapes through holes 152, thereby assisting the actuation of valve 156 forwardly in cylinders 60 and 110 and the residual air passes through holes 154.

From the foregoing, it will be apparent to one skilled in the art that herein is disclosed a simple compact device for charging a firearm that will hold the bolt in a recoil position and also assist in holding such bolt in the battery position.

While the form of embodiment of the invention herein disclosed constitutes a preferred form, it is understood that other forms might be adapted as may come within the scope of the claims which follow.

I claim:

1. In a firearm, a receiver, a bolt reciprocably mounted for movement between a battery and recoil position in said receiver, a pair of charger cylinders mounted inside said receiver, an inner piston fixedly secured in each of said cylinders in the forward end thereof, a tubular piston slidably mounted over each of said inner pistons and operable between a battery and recoil position in said cylinders, and means movably secured to each of said tubular pistons for moving said bolt to a battery or recoil position.

2. In a firearm, a receiver, a bolt reciprocably mounted for movement between a battery and recoil position in said receiver, a pair of charger cylinders mounted inside said receiver, an inner piston fixedly secured in each of said cylinders in the forward end thereof, a tubular piston slidably mounted over each of said inner pistons, means associated with each of said inner pistons and tubular pistons for moving said tubular pistons to a battery or recoil position in said cylinders, and means movably secured to each of said tubular pistons for moving said bolt to a battery or recoil position.

3. In a firearm, a receiver, a bolt reciprocably mounted for movement between a battery and recoil position in said receiver, a pair of charger cylinders mounted inside said receiver, an inner piston fixedly secured in each

of said cylinders in the forward end thereof, a tubular piston slidably mounted over each of said inner pistons, means associated with each of said inner pistons and tubular pistons for moving said tubular pistons to a battery or recoil position in said cylinders, screw means associated with each of said tubular pistons and movable therewith, and means movably secured to each of said screw means for moving said bolt to a battery or recoil position.

4. In a firearm, a receiver having a pair of spaced-apart longitudinally disposed holes on the inside thereof, a bolt reciprocably mounted for movement between a battery and recoil position in said receiver, a bridge fixedly secured in the front end of said receiver and being provided with recesses longitudinally aligned with said holes in said receiver, said bridge being provided with a bore forwardly of each of said recesses and aligned therewith, a charger cylinder mounted in each of said holes and secured on the front end thereof in said recess of said bridge, an inner piston having a reduced front end portion fixedly secured in each of said bores of said bridge, a tubular piston slidably mounted over each of said inner pistons, means associated with each of said inner pistons and tubular pistons for moving said tubular pistons to a battery or recoil position, screw means associated with each of said tubular pistons and movable therewith, and means movably secured to each of said screw means for moving said bolt to a battery or recoil position.
5. The combination defined in claim 4 wherein said screw means comprises an inner screw fixedly secured on the forward end thereof in said bridge and having screw threads on the exterior thereof, an outer screw rotatably mounted on said inner screw and being rotatably secured on the rear end thereof to said tubular piston, said outer screw having threads on the interior thereof for cooperation with said threads on said inner screw and having threads on the exterior thereof for moving said last-mentioned means therealong whereby said bolt may be moved to a battery or a recoil position.

6. In a firearm, a receiver having a pair of spaced-apart longitudinally disposed holes on the inside thereof, a bolt reciprocably mounted for movement between a battery and recoil position in said receiver, a bridge fixedly secured in the front end of said receiver and being provided with recesses longitudinally aligned with said holes in said receiver, said bridge being provided with a bore forwardly of each of said recesses and aligned therewith, a charger cylinder mounted in each of said holes of said receiver and secured on the front end thereof in said recess of said bridge, a tubular piston slidably mounted in each of said cylinders, an inner piston having a reduced front end portion fixedly secured in each of said bores of said bridge, said inner piston being provided with an intermediate portion rearwardly of said front end and an enlarged head portion on the rear end thereof arranged to slidably receive said tubular piston thereon, a reduced bore being provided in the forward end of said tubular piston arranged for slidable engagement with said intermediate portion of said inner piston, means associated with each of said inner pistons and tubular pistons for moving said tubular pistons to a battery or recoil position, screw means associated with each of said tubular pistons and movable therewith, and means movably secured to each of said screw means for moving said bolt to a battery or recoil position.

7. In a firearm, a receiver having a pair of spaced-apart longitudinally disposed holes on the inside thereof, a bolt reciprocably mounted for movement between a battery and recoil position in said receiver, a bridge fixedly secured in the front end of said receiver and being provided with recesses with reduced bores leading forwardly therefrom and longitudinally aligned with said holes in said receiver, a charger cylinder mounted in each of said holes of said receiver and secured on the

front end thereof in said recess of said bridge, each of said cylinders being provided with a rearwardly extending slot in the upper part thereof, a tubular piston slidably mounted in each of said cylinders and having an upwardly extending bracket receivable in said slot having a bearing rotatably mounted in the upper part thereof, said tubular pistons being provided with a reduced bore in the front end and a plug threadably secured in the rear end thereof, an inner piston having a reduced front end portion fixedly secured in each of said bores, said inner piston having an enlarged head portion on the rear end thereof receivable in said tubular piston and an intermediate portion receivable in said reduced bore, an inner screw fixedly secured to said bridge approximately above each of said cylinders, a rotatable outer screw fixedly secured to said bearing of said bracket and being threadably mounted on said inner screw for movement therealong, a nut threadably mounted on each of said outer screws and having an upwardly extending lug portion, means associated with each of said inner pistons and tubular pistons for moving said tubular pistons to a battery or recoil position whereby said movement of said tubular pistons moves said nuts therealong, and means associated with said bolt cooperating with said lugs of said nuts for moving said bolt to a battery or recoil position.

8. In a firearm, a receiver, a bolt reciprocably mounted for movement between a battery and recoil position in said receiver, a solenoid controlled source of air pressure mounted on the inside of said receiver, a pair of chargers mounted inside said receiver, a first passage means connecting said source of air pressure with said chargers whereby said chargers are moved to a recoil position, a second passage means connecting said source of air pressure with said chargers whereby said chargers are moved to a battery position, screw means associated with each of said chargers and movable therewith, and means movably secured to each of said screw means for moving said bolt to a battery or recoil position.

9. The combination defined in claim 8 wherein said screw means comprises an inner screw fixedly secured on the forward end thereof in said bridge and having screw threads on the exterior thereof, an outer screw rotatably mounted on said inner screw and being rotatably secured on the rear end thereof to said tubular piston, said outer screw having threads on the interior thereof for cooperation with said threads on said inner screw and having threads on the exterior thereof for moving said last-mentioned means therealong whereby said bolt may be moved to a battery or a recoil position.

10. In a firearm, a receiver, a bolt reciprocably mounted in said receiver, a solenoid controlled source of air pressure mounted on the inside of said receiver, a bridge fixedly secured in the front end of said receiver, a pair of charger cylinders mounted inside said receiver, an inner piston fixedly secured in each of said cylinders in the forward end thereof, a tubular piston slidably mounted over each of said inner pistons for movement between a recoil and battery position in said cylinder, a first passage means in said receiver and said bridge connecting said source of air pressure with said cylinders, each of said cylinders being provided with a pressure operated valve in the front end thereof constructed to admit air pressure therethrough whereby said air pressure impinging on said tubular piston moves said tubular piston to a recoil position, a second passage means in said receiver and said bridge connecting said source of air pressure with a forwardly extending tunnel in said inner pistons whereby said air pressure impinging on said tubular pistons moves said tubular pistons to a battery position, screw means associated with each of said tubular pistons and movable therewith, and means movably secured to said screw means for moving said bolt to a battery or recoil position.

11. In charger means for reciprocating a slidable bolt

in a firearm receiver, first screw means fixedly secured in the receiver, second screw means threadably engageable on said first screw means, fixed means on the charger means for rotatably securing said second screw means thereto, third screw means threadably engageable on said second screw means and adapted to move therealong in response to the rotation of the latter, means engaging said third screw means with the bolt, and means for longitudinally reciprocating the charger means to impart corresponding movement to said second screw means along said first screw means whereby the threaded engagement therebetween simultaneously rotates said second screw means to move said third screw means therealong and thereby increase the extent of travel of the bolt relative to the travel of the charger means by a distance substantially equivalent to the length of said second screw means.

12. In charger means for reciprocating a slidable bolt in a firearm receiver, a tubular charger piston slidably mounted in the receiver parallel to the bolt, a fixed screw secured at the front end thereof in the forward end of the receiver, a hollow screw having an inferiorly threaded portion engageable with said fixed screw, bracket means on said tubular piston for rotatably securing said hollow screw thereto in threadable engagement with said fixed screw, a nut threadably mounted on said hollow screw for longitudinal movement therealong in response to rotation of the latter, said nut having a radially projecting lug engageable with the bolt, and means for longitudinally reciprocating said tubular piston to impart corresponding movement to said hollow screw along said fixed screw whereby the threaded engagement therebetween simultaneously rotates said hollow screw to move said nut therealong and thereby increase the extent of travel of the bolt relative to the travel of said tubular piston by a distance substantially equivalent to the length of said hollow screw.

13. In charger means for reciprocating a slidable bolt in a firearm receiver, a pair of hollow cylinders fixedly disposed in either side of the receiver below and parallel to the bolt, a tubular piston slidably disposed in each of said hollow cylinders, an inner screw fixedly mounted at the front end thereof in the forward end of the receiver between the bolt and each of said tubular pistons, an offset bracket fixedly secured to the rear end of each of said tubular pistons, a hollow outer screw having an exteriorly threaded portion and an inferiorly threaded portion engageable with each of said fixed inner screws and having a rearwardly projecting portion journaled in said offset bracket, a nut threadably mounted on each of said hollow screws for longitudinal movement therealong in response to rotation of the latter, each of said nuts having a lug projecting radially therefrom in engagement with the underside of the bolt, said inner screws and said inferiorly threaded portions of said hollow outer screws having mating left hand threads, said nuts and said exteriorly threaded portions of said hollow outer screws having mating right hand threads, and means for simultaneously reciprocating said tubular pistons in said hollow cylinders to impart corresponding movement to said hollow outer screws along said fixed inner screws whereby the engagement of said right hand threads therebetween simultaneously rotates said hollow screws to move said nuts therealong by means of the engagement of said left hand threads therebetween and thereby increase the extent of travel of the bolt relative to the travel of each of said tubular pistons by an amount substantially equivalent to the length of each of said hollow screws.

14. In a firearm having a receiver and a bolt slidably mounted therein for reciprocal movement between battery and recoil positions, charger means for reciprocating the bolt comprising in combination, a hollow cylinder fixedly mounted in the receiver parallel to the bolt and extending rearwardly to terminate adjacent the rear end of the re-

ceiver, a tubular piston slidably mounted in said cylinder for reciprocal movement therein, an inner piston fixedly mounted at the front end thereof in the forward end of the receiver to extend rearwardly into said hollow cylinder and into the hollow interior of said tubular piston, said inner piston having an enlarged head portion at the rear end thereof cooperating with said tubular piston to limit movement thereof in either direction to an amount substantially half of the length of said hollow cylinder, an inner screw having left hand threads on the exterior periphery thereof and fixedly secured at the front end thereof adjacent the front end of said hollow cylinder to extend rearwardly between the bolt and said tubular piston parallel thereto, a hollow outer screw having left hand threads on the interior periphery thereof for mating engagement with said left hand threads on said inner screw and having right hand threads on the exterior periphery thereof, a bracket projecting radially from the rear end of said tubular piston for connecting said outer screw thereto, said bracket having a bearing portion therein for rotatably engaging the rear end of said outer screw, a nut having right hand threads engageable with said threaded exterior periphery of said outer screw for longitudinal movement therewith in response to rotation of the latter, a radially disposed lug on said nut for effecting non-rotatable engagement thereof with the bolt, a fluid pressure means for reciprocating said tubular piston to reciprocate said outer screw jointly therewith, said left hand threads on said inner screw and within the interior periphery of said outer screw being arranged to impart rotation to the latter during the reciprocating movement thereof, said right hand threads on the exterior periphery of said outer screw and within said nut being arranged to effect relative movement therebetween simultaneously with the longitudinal movement of said outer screw relative to said inner screw whereby the total travel of the bolt is substantially equivalent to the travel of said outer screw on said inner screw plus the travel of said nut on said outer screw.

15. In a charger means for a firearm having a receiver and a bolt slidably mounted therein for reciprocal movement between battery and recoil positions, the combination of a hollow cylinder fixedly mounted in the receiver parallel to the bolt, an inner piston having an elongated body portion fixedly secured at the forward end thereof in the front end of the receiver and extending rearwardly in said hollow cylinder to terminate in an enlarged head portion, a tubular piston slidably mounted in said hollow cylinder and having a closed rear end and a reduced bore section at the front end thereof for slidably receiving said elongated body portion of said inner piston therethrough whereby said enlarged head portion is in slidable engagement with the interior periphery of said tubular piston,

- means connecting said tubular piston to the bolt, said inner piston having a first channel therein terminating in an exit adjacent the front face of said enlarged head portion and a second channel opening between the interiors of said hollow cylinder and said tubular piston, a source of fluid pressure medium connected to the forward end of said hollow cylinder and to the forward end of said second channel in said inner piston, means for directing said fluid pressure medium through said hollow cylinder and against the front face of said reduced bore section of said tubular piston to impart rearward movement thereto for retracting the bolt to recoil position, said first channel and said inner piston being arranged to admit a portion of said fluid pressure medium into the interior of said tubular piston and against said closed rear end thereof for increasing the rearward force imparted thereto, solenoid means for blocking access to said hollow cylinder and simultaneously uncovering access to said second channel in said inner piston, and means for directing said fluid pressure medium into said tubular piston between the rear face of said reduced bore section therein and the front face of said enlarged head portion to reverse the travel of said tubular piston for returning the bolt to battery position whereby the lesser pressure area of the rear face of said reduced bore section in comparison to the pressure area on the front face thereof requires a correspondingly lesser amount of fluid pressure to return the bolt to battery position than that required for retraction thereof to recoil position.
- 30 16. The combination defined in claim 15 including valve means slidably disposed for limited reciprocal movement in the forward end of said hollow cylinder for controlling the entry of fluid pressure medium therein, and a plurality of radially disposed exhaust ports in the front end of said hollow cylinder opening into the path of rearward movement imparted to said valve means during the passage of fluid pressure medium therethrough upon recoil of the bolt whereby said exhaust ports are operative only during return movement of the bolt toward battery position.
